UNITED STATES PATENT OFFICE.

HARRY L. MILLNER, OF MORGANTON, NORTH CAROLINA.

GAS-PRODUCER.

1,312,411.

Specification of Letters Patent.

Patented Aug. 5, 1919.

Application filed September 9, 1918. Serial No. 253,194.

To all whom it may concern:

Be it known that I, HARRY L. MILLNER, a citizen of the United States, residing at Morganton, in the county of Burke, State 5 of North Carolina, have invented certain new and useful Improvements in Gas-Producers, of which the following is a description, reference being had to the accompanying drawing and to the figures of reference 10 marked thereon.

My invention relates to improvements in gas producers and particularly to grates therefor.

The object of my invention is to provide 15 an apparatus of this character, in which tarry caking fuels, as well as saw-dust, spent tan bark, peat and the like, having a high percentage of moisture, may be readily handled and perfectly gasified, preventing the 20 formation of chimneys through the fuel bed. Such a formation of chimneys through the fuel bed results in an uneven action of the air blasts and greatly impairs the quality of the gas produced. The present invention 25 wholly eliminates this objection.

Another object of my invention is to provide a machine in which the fuel mass is thoroughly stirred, breaking up the arches, cakes and chimneys and thus makes the continuous 30 operation of the produce possible.

A still further object of my invention is to provide a simple, cheap and effective structure to accomplish the foregoing objects, which has certain details of structure 35 and combination of parts hereinafter more fully set forth.

In the accompanying drawings:—

Figure 1 is a vertical transverse sectional view of a gas producer provided with my 40 invention;

Fig. 2 is a top plan view of the revolving basket;

Fig. 3 is a side elevation of Fig. 2, showing one end partly broken away;

Fig. 4 is a top plan view of the stationary grate;

Fig. 5 is a transverse sectional view of one of the sections of which the stationary grate is formed.

Referring now to the drawings, 1 represents a gas producer which is of any well

known form and therefore needs no further description. The lower end of the fire pot 2 below the fire brick 3 is provided with a number of angle iron brackets 4 bolted 55 or otherwise rigidly secured to the shell 5 and arranged with the horizontal portion 6 in position shown in Fig. 1 of the drawings. The angle iron brackets 4 are provided on the under face of the horizontal 60 portion, with the webs 7 forming means by which the stationary grate is supported as will be hereinafter more fully described. Carried by the base upon which the producer is supported is a central standard 8 65 having its upper end 8' reduced forming the shoulder 9 forming a support for the stationary grate 10 as shown in Fig. 1 of the drawings.

The stationary grate 10 is as shown in 70 Fig. 4 of the drawings, formed of six sections 11, V shaped in plan view having their inner ends curved to fit against the reduced portion 8' of the standard and resting upon the shoulder 9. The outer edges of the sections 75 are curved to form a circular grate as fully shown in Fig. 4 of the drawings and the same being of a diameter considerably less than the interior diameter of the shell 5 as shown in Fig. 1 of the drawings. Each 80 section is composed of the outer flange 12 entirely surrounding the same and carrying the V shaped grate bars 13 arranged tangentially to the axis of the grate. The outer edge of each grate section is provided with 85 two outwardly extending parallel arms 14 and 15 bolted to the webs 7 of the brackets 4 by means of bolts 16 whereby the same is rigidly supported in the lower end of the producer: 90

The upper face of the angle iron brackets 4 has bolted thereto the upwardly extending arms 16', their upper ends provided with rollers 17, upon which the rotary basket 18 rests and is free to rotate, as will 95 be later described.

The rotary basket 18 is of a circular basket like form, having a flange 19 entirely surrounding the same and resting upon the rollers 17. The bottom of the basket is provided with an opening 20 of a size considerably less than the top of the basket and 100

arranged adjacent one side or eccentrically, thus giving a varying angle to the slope and length of the sides entirely around the basket. This rotary basket, as shown, is 5 made up of a number of sections bolted together by bolts 20', whereby any section may be replaced when broken. One of the said long sections is provided with an inwardly extending tongue 21, having an 10 opening 22 adapted to receive the reduced portion of the standard and thereby the basket is maintained in position in its rotation, as will be readily understood. The sections of the rotary basket are formed 15 with flanges 24, through which bolts pass and by means of which grate bars 25 are supported. The abutting faces of the flanges are cut away, as indicated at 26, forming air passages 27 to allow the upward 20 passage of air to cool the flanges and prevent warping thereof. The outer lower edge of the flange of the basket is provided with teeth 28 forming a gear, with which meshes the pinion 29 and which is rotated 25 in any desired manner and by means of which the basket is rotated, as will be readily understood.

The stationary grate, as shown, is of a size 30 to at all times cover the opening in the rotary basket, so that the sawdust or other gas producing fuel is prevented from passing from the grate through said opening. The fuel, as is understood, rests in the basket-like grate and above it, and upon the rotation 35 of the basket the fuel is grasped thereby and twisted upon itself, and at the same time every portion is progressively subjected to an upwardly heaving motion, due to the unequal length and slope of the basket sides 40 as they travel around in the rotation thereto. As the ash works down to the opening in the bottom, it is dragged across the grate bars of the stationary grate and forced therethrough to the ash pit, thus doing away 45 with the necessity of raking. This operation on the fuel absolutely prevents the same arching across above the grate to form cavities in the form of chimneys and thus a more uniform and better gas is produced.

50 It will be understood that I do not wish to be limited to the exact construction of the basket like grate shown and which has the motion imparted to it to give the combined twisting, heaving and scraping motions to the fuel bed, but it will be obvious that other arrangements may be devised for carrying out this object.

Having thus fully described my invention, what I claim as new and desire to secure by Letters Patent, is:—

60 1. A gas producer comprising a furnace, a stationary grate and a rotary basket like grate having an opening directly above the stationary grate, said rotary basket like 65 grate having sides of unequal slope and

length, whereby the movement of said basket like grate causes an upward heaving motion of the fuel above and the ash is dragged across the grate bars of the stationary grate.

2. A gas producer, comprising a furnace, 70 a stationary grate, a rotary basket like grate having an opening in its bottom eccentrically arranged forming sides of unequal slope and length and adapted to cause an upward heaving motion of the fuel above. 75

3. A gas producer, comprising a furnace, stationary grate, a rotary basket like grate having an opening in its bottom eccentrically arranged and forming sides of unequal slope and length and adapted to cause an upward heaving motion of the fuel above, and means for rotatably supporting the rotary grate adjacent its upper end and allowing the lower edge to freely move upon the stationary grate. 80

4. A gas producer, comprising a furnace, a stationary grate, a rotary basket like grate having an opening in its bottom eccentrically arranged and forming sides of unequal slope and length and adapted to cause 85 an upward heaving motion of the fuel above, rollers carried by the furnace above the stationary grate, and a flange carried by the upper edge of the rotary grate and traveling upon the said rollers. 90

5. A gas producer, comprising a furnace, a stationary grate, a standard supporting the center of the said grate, a rotary basket like grate having an opening in its bottom eccentrically arranged and forming sides of 100 unequal slope and length and adapted to cause an upward heaving motion of the fuel above, an ear extending into said opening and having an opening receiving the standard for centrally supporting the grate, 105 and means for rotatably supporting the upper end of the rotary grate. 95

6. A gas producer, comprising a furnace, a stationary grate in the lower end thereof, a standard having a reduced upper end 110 passing centrally through the stationary grate and supporting the same, a rotary basket like grate having an opening in its bottom eccentrically arranged and forming sides of unequal slope and length and adapted to cause an upward heaving motion of the fuel above, an ear carried by the lower end of the grate and extending into said opening and having an opening receiving the standard for centrally supporting the same, 115 rollers carried by the furnace, a flange carried by the upper edge of the rotary grate and resting upon rollers, gear teeth carried by the lower face of the flange on the outside of the rollers, and a pinion meshing with said gear teeth for rotating the grate. 120

7. A gas producer comprising a furnace, a stationary grate adjacent its lower end, a rotary basket like grate above the stationary grate having an eccentrically arranged open- 125 130

ing in its lower edge just above the grate and constructed to cause an upward heaving of the fuel, whereby a portion of the fuel is supported by the stationary grate and the 5 body of fuel prevented from rotating with the basket like grate.

In testimony whereof, I affix my signature, in the presence of two witnesses.

HARRY L. MILLNER.
